PORTABLE LAMP

Bert A. Dickerson, Decatur, Ill., assignor to Faries Manufacturing Company, Decatur, Ill., a corporation of Illinois

Application March 13, 1937, Serial No. 130,624

4 Claims. (Cl. 240—81)

My invention relates more specifically to those lamps which are designed to entirely shield the light source from the eyes of the user while distributing the light upon the working plane or upon a desk or table where it is needed.

The principal object of my invention is the production of a portable lamp of increased efficiency, owing to the construction making available a larger number of lumens.

10 A further object is to attain that result by an exceedingly simple and inexpensive construction.

My means of accomplishing the foregoing objects may be more fully comprehended by having reference to the accompanying drawings, which 15 are hereunto annexed and are a part of this specification in which:

Fig. 1 is a side elevation of my lamp with parts broken away and in sections showing the light distribution.

20 Fig. 2 is a vertical sectional view.

Fig. 3 is a detail of a portion of the lamp stand in perspective.

Fig. 4 is a detail of another portion of the stand in perspective.

25 Similar reference numerals refer to similar parts throughout the entire specification.

As shown in the drawings, my lamp consists of a base 1 from which extends upwardly a standard. This standard is preferably composed of a plurality of spindles 2, 3, and 4, which, as seen in the detail views, are provided with a central opening 5 which slips over a pipe or tube 6 which is secured to the base 1 and provides a passage for the electrical conductors (not shown).

30 Though I have shown a specific form of enclosure for the tube, it will be clear that any desired enclosing means may be employed. An ornamental appearance may be imparted to the standard by inserting one or more discs 7 below 35 and above the spindles 2, 3 and 4. At the upper end of the tube 6, I mount a short Electrolier keyless socket 8.

In this socket I mount an electric lamp bulb 9. Surrounding the socket 8 is a cup member 10 which is preferably provided with straight cylindrical sides 11 clearly seen in the sectional view.

Inside this cup 10 and snugly telescoping inside the straight sides 11 I mount a flaring reflector 12 or holder 12, the lower portion of which is provided with slots 12a to furnish a spring tension against the sides 11 for taking up inaccuracy or any variation in the cup 10 or the holder 12, and the use of such slots permits the holder to resiliently and adjustably engage the cup member.

The walls of the holder 12 flare outwardly from the top edge of the straight side walls 11 of the cup 10, and terminate at a point in line with the filament 24 of the lamp bulb 9. The inner surface of this flaring portion is provided with a coating of suitable reflecting media thus forming a supplemental reflector so that the light rays impinging thereon are reflected and redirected upwardly where they impinge upon the main reflector 13. The main reflector 13 is preferably supported by a stamped frame 14 having oppositely extending leg portions 14a, 14b respectively, projecting from a central upwardly concave flange 15, and having their lower ends flattened as illustrated and preferably riveted to the holder or supplemental reflector 12 adjacent its upper edge. In flange 15 there is provided a centrally threaded opening 16 into which is fitted a threaded portion 17 of the finial 20, the flange 18 of which has an annulus 18a on the under side adjacent its periphery for circumferential clamping of reflector 13. Finial 20 with its flange 18 and screw portion 17 serves to press the reflector 13 tightly upon the upwardly concave flange 15 of frame 14 thus holding it firmly in place.

Surrounding the recess 19 is a downwardly concave annular portion 21 in the reflector 13 so shaped as to receive and redirect a portion of the direct light rays from the source and the reflected ones from the supplemental reflector 12 onto the working plane.

The main reflector 13 is provided with an enlarged annular downwardly concaved portion 22 the edge 23 of which extends below the plane 35 of the upper edge of the supplemental reflector 12. In this manner I completely shield the electric lamp bulb 9 from the eyes of the user. But the light rays are reflected and redirected over a comparatively large surface.

It will be clear to those skilled in the art that I have utilized the support for the reflector supporting frame as a supplemental reflector thus increasing the efficiency of the lamp without materially increasing the expense of manufacture. 45 Moreover, it will be seen that numerous designs may be produced simply by varying the positions of the discs 7 and the spindles 2, 3 and 4 without any additional expense. The main and supplemental reflectors are preferably made of opaque 50 material though obviously they may be constructed of another material if desired.

Having described my invention, what I regard as new and desire to secure by Letters Patent is:

- 5 1. A stand lamp comprising a pedestal, a cup shaped member at the top of the pedestal, an upwardly flaring opaque member having its lower portion adjustably and frictionally engaged by the cup member, a lamp socket in said cup member, an electric lamp in said socket, the upper edge of the member being substantially in alignment with the filament of the lamp, a reflector supporting frame secured to said flaring member, reflective means within the member, a concave downwardly facing unitary reflector supported by said frame and having its lower edge extending substantially below the filament of the lamp, and means for securing said concave reflector to the top portion of the frame, axially of the stand lamp.
- 10 2. A stand lamp comprising a pedestal, a cup shaped member at the top of the pedestal, an upwardly flaring opaque member having its lower portion frictionally engaged by the cup member, a lamp socket in said cup member, an electric lamp in said socket, the upper edge of the member being substantially in alignment with the filament of the lamp, a reflector supporting frame secured to said flaring member, a reflecting surface within the member, a concave downwardly facing unitary reflector supported by said frame and having its lower edge extending substantially below the filament of the lamp, and means for
- 15 30 35 securing said concave reflector to the frame, said concave reflector having a central recess to receive the top portion of the frame; and said securing means comprising a finial threadedly engaging the frame, substantially axially of the stand lamp.
3. In a stand lamp, a base, a tube which extends upwardly therefrom, a plurality of ornamental members surrounding said tube, a cup adjacent the upper end of said tube, a lamp socket threadedly engaging the tube and assembling said cup upon said tube, an electric bulb, an upwardly flaring member having its lower portion telescopically engaging said cup, reflecting means in said member, the upper edge of said member being in a plane with the filament of the bulb, a concave reflector having a central concavity of relatively small radius and an outer concavity of greater radius carried by said frame, the lower edge of the concave reflector extending below the upper edge of the flaring member, and means engaging the central concavity for attaching the concave reflector to the frame.
4. In a stand lamp, a base, a tube which extends upwardly therefrom, an electric lamp bulb supported by said tube, ornamental means enclosing said tube, a cup secured adjacent the upper end of said tube, a lower reflector having its walls flaring outwardly and upwardly mounted in said cup, the upper edge of said reflector being substantially in a plane with the filament of the bulb, a supporting frame secured to said lower reflector, a concave upper reflector carried by said frame and having its lower edge extending substantially below the upper edge of the lower reflector; the lower portion of the lower reflector being slotted to resiliently and adjustably support said reflector in said cup.

BERT A. DICKERSON.
